(57) **CLAIM**

The ornamental design for an ice fishing rod handle, as shown and described.

DESCRIPTION

FIG. 1 is a side perspective view of an ice fishing rod handle showing the new design;

FIG. 2 is a top view thereof.

FIG. 3 is a front view, relative to FIG. 4.

FIG. 4 is a side view thereof, the opposite side being a mirror image.

FIG. 5 is a rear view, relative to FIG. 4; and,

FIG. 6 is a bottom view thereof.

The broken lines depict environment and are for illustrative purposes only and form no part of the claimed design.

1 Claim, 2 Drawing Sheets

FIG. 4.

FIG. 5.

FIG. 6.
